(57) **CLAIM**

The ornamental design for a fold-up workshop, as shown and described.

DESCRIPTION

FIG. 1 is a top, front, and side perspective view showing my new design;

FIG. 2 is a front elevational view thereof;

FIG. 3 is a top plan view thereof; and,

FIG. 4 is a right side elevational view thereof, the left side being a mirror image of that shown.

Throughout the various figures of the drawings, certain views are not provided. The omission of a particular view is intended to convey that the elements depicted are plain and unornamented in that omitted view, or that the particular ornamental appearance in that view is simply not claimed. Where included, broken lines showing environment or structure are for illustrative purposes only and form no part of the claimed design.
